UNITED STATES PATENT OFFICE.

ARTHUR C. McBRIDE, OF SAN DIEGO, CALIFORNIA, ASSIGNOR TO CHALON E. CORSON
AND WILLIAM A. WRIGHT.

BRAKE-BAND-RELINING MACHINE.

Application filed November 12, 1919. Serial No. 337,602.

To all whom it may concern:

Be it known that I, ARTHUR C. McBRIDE, a citizen of the United States, residing at San Diego, in the county of San Diego and State of California, have invented certain new and useful Improvements in Brake-Band-Relining Machines, of which the following is a specification.

My invention relates to a machine to facilitate the relining of brake bands and the objects of my invention are: First, to provide a machine of this class whereby the brake band lining may be drilled and countersunk while in position on the brake band; second, to provide a machine of this class with power operated means for riveting the rivets in the brake bands; third, to provide a machine of this class in which the drill and countersinking apparatus is combined with the riveting portion of the apparatus; fourth, to provide an apparatus of this class in which the separate operating parts are contiguous and supported by means of one supporting member; fifth, to provide a novelly constructed drill, countersink and supporting pilot for brake bands; sixth, to provide a novelly constructed riveting apparatus and seventh, to provide a machine of this class which is very simple and economical of construction, durable, easy to operate and which will not readily deteriorate or get out of order.

With these and other objects in view as will appear hereinafter, my invention consists of certain novel features of construction, combination and arrangement of parts and portions as will be hereinafter described in detail and particularly set forth in the appended claims, reference being had to the accompanying drawings and to the characters of reference thereon which forms a part of this application, in which:

Figure 1 is a side elevational view of the machine and showing portions broken away; Fig. 2 is in section to facilitate the illustration; Fig. 3 is a top or plan view thereof minus the base and foot levers; Fig. 3 is a fragmentary sectional view through 3-3 of Fig. 1; Fig. 4 is a sectional view through 4-4 of Fig. 1 and Fig. 5 is a sectional view through 5-5 of Fig. 2 on an enlarged scale.

Similar characters of reference refer to similar parts and portions throughout the several views of the drawings.

The base 1, vertical support 2, table 3, supporting frame 4, motor 5, drive shaft 6, anvil 7, worm pinion 8, worm gear member 9, drill and countersink member 10, gauge 11, presser foot member 12, presser foot member support 13, lever 14, rod 15, foot lever 16, hammer plunger 17, cylinder 18, air conductor 19, air conductor 20, valve 21, valve rod 22, and foot lever 23 constitute the principal parts and portions of my brake band relining machine.

The base member 1 is preferably circular and of a sufficient size to form a base or support for the machine and is provided centrally with an upwardly flanged lug in which is supported the vertical support 2 which is an ordinary pipe of suitable length threaded on both ends and secured on the upper end is a table member 3, annular in form upon which is secured the supporting frame 4 which is preferably a cast iron frame in bifurcated form shaped as shown best in the drawings. Also mounted on this table 3 on the flange 4^a of the member 4 is the motor 5. Directly connected to this motor 5 is a main shaft 6 which is journaled in a lug 4^b on the side of the frame 4 and extending forwardly to near the extended end of the portion 4^c of the member 4. Mounted on the extended end of this shaft 6 is a worm pinion 8 which engages a worm gear member 9 both of which are revolubly mounted in a housing 4^d on the extended end of the member 4^c and held in adjusted position therein by means of a sleeve 9^a screwed into the lower end of the housing 4^d and provided with a lock nut 9^b for holding it in position. The worm gear member 9 is provided with a central hole 9^c, the upper end of which is tapered, adapted for the combined drill and countersinking member 10 to be wedged therein. Mounted over the upper end of the housing 4^d is a curved surface gauge member 11 which is supported by means of springs 11^a, the lower ends of which rest in recesses in the housing 4^d. This member 11 is provided with a central hole 11^b adapted to permit the upper end

of the member 10 to protrude therethrough when the springs 11^a are compressed. In the one side of the housing 4^a is an adjusting screw 11^c, shown in Fig. 1 of the drawings. This adjusting screw is mounted in a threaded hole in the housing 4^a and is provided with a hole adapted to receive a pin 11^a mounted on the member 11. This adjusting screw 11^c is adapted for a stop 5 for the member 11 in its downward movement and is adapted to regulate the depth of the countersink in the brake lining by regulating the depression of the gauge member 11. Mounted immediately over the center of the member 11 and reciprocally mounted in the head 4^c is a presser foot member support 13 which is actuated by means of the lever 14 pivoted on a bolt 14^a, said member 13 being connected by means of 10 a pin 13^a on the outwardly extended end of which is a roller 13^b which is mounted in a slot in the end of the lever 14. The opposite end of the lever 14 is connected with the rod 15 which extends downwardly and is secured to one end of the foot lever 16 which is pivotally mounted on a shaft 1^a on the base 1. Mounted on the rod 15 is a compression spring 15^a tending to hold the rod 15 downwardly which in turn holds the 15 member 13 up in the position shown best in Figs. 1 and 4 of the drawings. Secured to the presser foot member support 13 by means of threads 12^a is the presser foot member 12 which is provided with a hole in 20 which is mounted a compression spring 12^b, the one end of which sets against a pilot 12^c, the other end is adapted to protrude from the lower end of the member 12. The end of this pilot 12^c is adapted to be inserted 25 in the hole in the brake band with the lining in position, when the lever 16 moved until the brake lining contacts with the member 11 depressing the same until the member 11 engages the adjusting screw 11^c thus drilling 30 and countersinking a hole in the brake lining, the drill and countersink 10 being revolved by means of the worm gear member 9 through the pinion 8 and shaft 6 operated by the motor 5. Adjustably mounted 35 on the member 4 in the portion 4^c is an anvil 7 which is threaded on its outer surface and adapted to screw into an enlarged portion 4^f of the member 4^c. This anvil member is provided with a lock nut 7^a adapted 40 to set up against the lower surface of the enlarged portion 4^f and hold the anvil member 7 in adjusted position. The upper end of this anvil member 7 is provided with a lug portion 7^b adapted for the rivet to rest 45 upon. Reciprocally mounted directly over this lug 7^b is a riveting plunger 17 provided with a reduced portion with a cup shaped end 17^a adapted for a head for the rivet on the opposite side of the brake band from the 50 lining. This plunger member 17 is reciprocally mounted in a cylinder 18 fitted into an enlarged portion 4^e of the bracket 4. This cylinder 18 is provided with several diameter chambers and the plunger 17 is also provided with several diameter portions. The cylinder 18 is provided with ports 18^a which extend downwardly and communicate with the lower end of one of the intermediate chambers in the cylinder 18. The plunger 17 is provided with a plurality of exhaust ports 17^c which communicate with a large port 17^d, which extend upwardly through the center of the plunger 17 to the upper end to permit air to pass from above the upper end of the plunger 17 and out through the ports 17^c to the outside when the plunger 17 is in certain relative position to the cylinder 18 which would be the down stroke of said plunger. The 55 plunger 17 is actuated upwardly by the air pressure against the enlarged portion 17^e of the plunger 17 until the plunger rises to a position so that the groove 17^f communicates with the enlarged portion 18^b of the cylinder 18 when it passes through the ports 17^e and around the upper end thereof to above the same causing the plunger to descend thus providing a rapid reciprocating action of the plunger 17 for riveting purposes. Communicating with the ports 18^a in the 60 cylinder 18 is an air conductor 19 which communicates with a chamber 21^a to which is secured another chamber 21^b and adapted to seat on the lower end of the chamber 21^b is a valve 21 which is actuated by the valve 100 rod 22 which extends downwardly and its lower end is pivotally connected with a foot lever 23 pivotally mounted on the shaft 1^a on the base member 1. Mounted on the rod 22 is a compression spring 22^a tending to hold said rod 22 downwardly so that the valve 21 is seated. However, upon the depression of the foot portion of the lever 23 the valve 21 will be raised to the position 105 shown by solid lines in Fig. 1 of the drawings, whereupon the air from a compressed air reservoir will pass through the conductor 20 into a chamber 21^b and through the valve 21, through the conductor 19 and into the ports 18^a for operating the riveting plunger 17 and that when the lever 23 is released the spring 22^a will close the valve 21, the air pressure is relieved and the plunger 17 will stop. 110 Though I have shown and described a particular construction, combination and arrangement of parts and portions I do not wish to be limited to this particular construction, combination and arrangement but desire to include in the purview of my invention the construction, combination and arrangement substantially as set forth in the appended claims. 115 It is obvious that with this construction there is provided a machine for relining 120 125

- brake bands which consists of means for drilling and countersinking the brake lining when in position on the brake band and guided by a pilot member engaging the hole 5 in the brake band; that the depth of the countersinking in the brake lining is adjusted by means of the adjusting screw 11^c which controls the movement of the member 11; that the rivets are riveted by means 10 of the plunger 17 in the one end of the rivet, supported by means of the anvil 7 adjustably mounted in the portion 4^c of the bracket 4 and both operations are regulated and controlled by the foot levers 16 and 15 23, while the operator's hands are free to hold the brake band and lining in position.
- Having thus described my invention what I claim as new and desire to secure by Letters Patent, is:
- 20 1. A device of the class described, including a combination revoluble drill and countersinking member, a presser foot member reciprocally mounted in axial alinement with the same and in close proximity thereto, a pilot member reciprocally and resiliently mounted in said presser foot member, and means for regulating the movement of said presser foot member.
2. A device of the class described, including a combination revoluble drill and countersinking member, a presser foot member reciprocally mounted in axial alinement with the same and in close proximity thereto, a pilot member reciprocally and resiliently mounted in said presser foot member, means for regulating the movement of said presser foot member, and a yieldable support mounted over said drill and countersinking member.
- 30 3. A device of the class described, including a combination revoluble drill and countersinking member, a presser foot member reciprocally mounted in axial alinement with the same and in close proximity thereto, a pilot member reciprocally and resiliently mounted in said presser foot member, means for regulating the movement of said presser foot member, a yieldable support mounted over said drill and countersinking member, and a stop means adapted to engage said support to limit its movements.
- 40 4. A machine of the class described, including a combination revoluble drill and countersinking member, a yieldable work support mounted over said drill and countersinking member provided with a central hole through which said drill and countersink protrudes, an adjustable stop means adapted to engage said support to limit its movements, a pilot member reciprocally mounted above said drill and countersink member, and foot lever means for reciprocating said pilot member into and out of engagement with the work upon said yieldable support.
5. A device of the character described, including a combination drill and countersink, a member movable relatively thereto, a pilot reciprocally and resiliently mounted in said member in axial alignment with the 70 drill and countersink, and means for operating said movable member.
6. The mechanism for perforating linings in registration with apertures of brake bands, which comprises a rotary boring 75 member, a work-supporting member, one of said members being movable toward and from the other, and a centering device in alignment with said boring member and movable thereby.
7. The mechanism for perforating linings in registration with apertures of brake bands, which comprises a work supporting member, a drilling and countersinking member, one of said members being movable 80 relatively to the other to drill and countersink a lining, and a guide in alignment with said drilling and countersinking member and movable longitudinally without affecting the position of work on said work supporting member.
8. The mechanism for perforating linings in registration with apertures of brake bands, which comprises a work supporting member, a drilling and countersinking 85 member, one of said members being movable relatively to the other to drill and countersink a lining, a guide in alignment with said drilling and countersinking member and means for regulating the movement 90 of said movable member to limit the penetration of said countersinking member.
9. The mechanism for drilling and countersinking brake band linings which comprises a revoluble drill and countersinking 105 tool and a guiding device in alignment therewith, said guiding device having a yieldingly supported member for registering the position of the drill from the opposite side of the work and adapted to be pushed 110 back by said drill.
10. A machine for drilling and countersinking a fabric brake lining in registration with apertures in a metal brake band which comprises an upwardly projecting tool having a drilling section and a countersinking section, means below the drilling section of said tool for rotating it, said drilling section being concealed by a lining and band positioned for drilling, means visibly indicating the position of said drilling section when concealed by a lining and band, said means being positioned to permit alignment therewith of a band aperture to effect registration of such aperture and the tool, and means for controlling the penetration of said tool into a lining on the band.
11. In a machine for drilling and countersinking linings in registration with apertures of brake bands, the combination with 120
- 125
- 130

- a revolute drilling and countersinking tool, of a member through which said tool projects, said member engaging a lining drilled by said tool to limit the penetration thereof, and a guide visibly indicating the position of said tool when concealed by a lining.
12. The mechanism for perforating linings in registration with apertures of brake bands, which comprises a rotary tool, a yielding support forming a rest for a lining and band and movable to bring a lining thereon into engagement with the tool, and a guide in alignment with the tool and adapted for registration with a band aperture.
13. The mechanism for perforating linings in registration with apertures of brake bands, which comprises a support forming a rest for a lining and band, a drilling and countersinking tool, one of said members being movable toward and from the other to effect drilling and countersinking of a lining on said support, and an adjustable stop for regulating the movement of said movable member to limit the penetration of said tool.
14. A mechanism for the purpose specified comprising, in combination, a rotary drilling and countersinking member and an aligning member in alignment with the drilling and countersinking member and adapted to engage the aperture in a brake band and visibly indicate the position of the drilling and countersinking tool when concealed by work, and means for causing relative movement between said band and the drilling and countersinking member after the aligning member has engaged one of the apertures.
15. A machine for the purpose specified comprising, in combination, a rotary drilling and countersinking member, a resiliently supported aligning member in alignment with the drilling and countersinking member adapted to engage the apertures in a brake band, means for causing relative movement between the said band and the drilling and countersinking member.
16. A mechanism for the purpose specified comprising, in combination, a rotary drilling and countersinking member and an aligning member in alignment with the drilling and countersinking member and adapted to engage the aperture in a brake band, and a pedal device operable to cause relative movement between the said band and the said drilling and countersinking member.
17. A machine of the character described comprising a rotary drilling and countersinking member, an aligning member comprising a yielding pin adapted to be engaged in an aperture in a brake band and to be pushed back therefrom under pressure of the drilling member, and manually operable lever mechanism for operating one of said members to effect operative engagement between said drilling and countersinking member and a lining on a band.
18. The combination with an apertured metal brake band forming a template for a lining thereon, of a tool having a drilling section and a countersinking section of larger diameter than the aperture in said band, said lining being disposed between said band and tool, means visibly indicating the position of said tool when concealed by said band, and means limiting the penetration of said lining by said tool.
19. In a machine of the class described, a revolute tool adapted both to countersink and drill a hole through a brake lining, means whereby the brake lining is centered by reference to the opening in the brake band to which it is to be attached and guided as said band and lining are moved with respect to said centering tool and means for accurately limiting the depth of penetration of said tool.
20. In a machine for drilling and countersinking linings in registration with apertures of brake bands, means comprising a revolute tool adapted both to drill and countersink a hole through a brake lining, means whereby the brake lining is positioned by reference to an opening in the brake band to which it is to be attached, and adjustable means forming a support for a lining for accurately limiting the depth of penetration of said tool.

In testimony whereof, I have hereunto set my hand at San Diego, California, this 7th day of November, 1919.

ARTHUR C. McBRIDE.

a revolute drilling and countersinking tool, of a member through which said tool projects, said member engaging a lining drilled by said tool to limit the penetration thereof, 5 and a guide visibly indicating the position of said tool when concealed by a lining.

12. The mechanism for perforating linings in registration with apertures of brake bands, which comprises a rotary tool, a 10 yielding support forming a rest for a lining and band and movable to bring a lining thereon into engagement with the tool, and a guide in alignment with the tool and adapted for registration with a band aperture. 15

13. The mechanism for perforating linings in registration with apertures of brake bands, which comprises a support forming a rest for a lining and band, a drilling and 20 countersinking tool, one of said members being movable toward and from the other to effect drilling and countersinking of a lining on said support, and an adjustable stop for regulating the movement of said movable 25 member to limit the penetration of said tool.

14. A mechanism for the purpose specified comprising, in combination, a rotary drilling and countersinking member and an aligning member in alignment with the drilling and countersinking member and adapted to engage the aperture in a brake band and visibly indicate the position of the drilling and countersinking tool when concealed by work, and means for causing relative 30 movement between said band and the drilling and countersinking member after the aligning member has engaged one of the 35 apertures.

15. A machine for the purpose specified 40 comprising, in combination, a rotary drilling and countersinking member, a resiliently supported aligning member in alignment with the drilling and countersinking member adapted to engage the apertures in a 45 brake band, means for causing relative movement between the said band and the drilling and countersinking member.

16. A mechanism for the purpose specified comprising, in combination, a rotary 50 drilling and countersinking member and an aligning member in alignment with the drilling and countersinking member and

adapted to engage the aperture in a brake band, and a pedal device operable to cause relative movement between the said band 55 and the said drilling and countersinking member.

17. A machine of the character described comprising a rotary drilling and countersinking member, an aligning member comprising a yielding pin adapted to be engaged in an aperture in a brake band and to be pushed back therefrom under pressure of the drilling member, and manually operable lever mechanism for operating one of said 60 members to effect operative engagement between said drilling and countersinking member and a lining on a band.

18. The combination with an apertured metal brake band forming a template for a 70 lining thereon, of a tool having a drilling section and a countersinking section of larger diameter than the aperture in said band, said lining being disposed between said band and tool, means visibly indicating the position of said tool when concealed by said 75 band, and means limiting the penetration of said lining by said tool.

19. In a machine of the class described, a 80 revolute tool adapted both to countersink and drill a hole through a brake lining, means whereby the brake lining is centered by reference to the opening in the brake band to which it is to be attached and guided as said band and lining are moved 85 with respect to said centering tool and means for accurately limiting the depth of penetration of said tool.

20. In a machine for drilling and countersinking linings in registration with apertures of brake bands, means comprising a 90 revolute tool adapted both to drill and countersink a hole through a brake lining, means whereby the brake lining is positioned by reference to an opening in the brake band 95 to which it is to be attached, and adjustable means forming a support for a lining for accurately limiting the depth of penetration of said tool.

In testimony whereof, I have hereunto 100 set my hand at San Diego, California, this 7th day of November, 1919.

ARTHUR C. McBRIDE.

Certificate of Correction.

It is hereby certified that in Letters Patent No. 1,576,138, granted March 9, 1926, upon the application of Arthur C. McBride, of San Diego, California, for an improvement in "Brake-Band-Relining Machines," an error appears in the printed specification requiring correction as follows: Page 4, line 86, claim 19, after the word "centering" insert the words *means and*; and that the said Letters Patent should be read with this correction therein that the same may conform to the record of the case in the Patent Office.

Signed and sealed this 13th day of April, A. D. 1926.

[SEAL.]

M. J. MOORE,
Acting Commissioner of Patents.
